United States Patent Office

Des. 208,065

Patented July 11, 1967

208,065

MEMORIAL LAMP

Alfonso A. Colletti, 95 Beckman Ave.,
North Tarrytown, N.Y. 10591

Filed Mar. 15, 1966, Ser. No. 1,475

Term of patent 14 years

(Cl. D48—20)

FIG. 1 is a front view of the memorial lamp.

FIG. 2 is a top view of the memorial lamp with the cover removed for convenience of illustration.

The supporting post in FIG. 1 is broken away to indicate indeterminate length.

I claim:

The ornamental design for a memorial lamp as shown and described.
